CLAIM

The ornamental design for a display device, as shown and described.

DESCRIPTION

FIG. 1 is a perspective view of the screen, outer frame, and casing of a display device according to the present design in a folded state;

FIG. 2 is a front view thereof;

FIG. 3 is a rear view thereof;

FIG. 4 is a left side view thereof;

FIG. 5 is a right side view thereof;

FIG. 6 is a top view thereof, with the bottom view being a mirror image thereof;

FIG. 7 is a perspective view of the screen, outer frame, and casing of the display device shown in an unfolded state;

FIG. 8 is a front view thereof;

FIG. 9 is a rear view thereof;

FIG. 10 is a left side view thereof;

FIG. 11 is a right side view thereof;

FIG. 12 is a top view thereof, with the bottom view being a mirror image thereof;

FIG. 13 is a front view of the screen, outer frame, and casing of the display device shown in an environment of use;

FIG. 14 is a perspective view of the casing of the display device shown separately to show aspects of the design that are not visible when combined;

FIG. 15 is an exploded perspective view of the casing of the display device shown separately to show aspects of the design not visible when combined; and,

FIG. 16 is an enlarged cross-sectional view of the display device taken in the direction of line 16-16 in FIG. 14.

(Continued)

The broken line showing of the icons in FIG. 13 depicts environment and forms no part of the claimed design.
